INVENTOR
Harry B. Miller
BY Howard P. Fairson
ATTORNEY.

ATTORNEY.

UNITED STATES PATENT OFFICE.

HARRY B. MILLER, OF SYRACUSE, NEW YORK.

DIE-STOCK.

1,273,082.

Specification of Letters Patent. Patented July 16, 1918.

Application filed March 8, 1917, Serial No. 153,475. Renewed April 27, 1918. Serial No. 231,280.

To all whom it may concern:

Be it known that I, HARRY B. MILLER, a citizen of the United States, and resident of Syracuse, in the county of Onondaga, in the 5 State of New York, have invented new and useful Improvements in Die-Stocks, of which the following, taken in connection with the accompanying drawings, is a full, clear, and exact description.

10 This invention relates to certain improvements in die stocks, and to automatic oil feeds for the same.

The primary object of the invention is to produce a device of this character capable 15 of operation upon articles of various sizes within a relatively extensive range of diameters.

A further object is to provide automatic and positive lubrication for the device.

20 Other objects and advantages relate to the construction and the details of the same, for accomplishing the above objects in a simple, inexpensive and efficient manner, as will appear from the following description taken 25 in connection with the accompanying drawings, in which—

Figure 1 is a top plan view of the device.

Fig. 2 is a side elevation of the same.

30 Fig. 3 is a cross section on line 3—3, Fig. 1.

Fig. 4 is a cross section on line 4—4,

Fig. 2.

35 Fig. 5 is a cross section on line 5—5, Fig. 4.

The stock comprises the usual base —1— having the usual adjustable sectional dies —2— held in place by bolts —3— and —4—, and the collar —5— alined with the opening between the dies —2— and adapted to 40 receive the boss —6— formed in connection with the base —7— of a cylindrical casing —8— comprising in connection with said base a cap —9— having a depending flange —10— telescopied outside said base.

The cap —9— may be secured to the base —7— in any suitable manner, as by screws —10— having a threaded engagement with the base and positioned in the slots —11— formed in the cap —9— concentric with a central opening —12— in registration with the opening between the dies —2—.

50 Within the casing —8— is positioned a plurality of guide wheels —13— rotatably mounted upon slidable bars —14— mounted to reciprocate in slots —15— formed in the

up-standing wall of the base —7— so that the wheels or rollers —13— may be adjusted toward and from each other to receive between them articles, such as pipes, 60 to be threaded, of varying diameters.

For the purpose of simultaneously moving all of the wheels or rollers radially of the casing —8—, each bar —14— is provided with a groove or depression —16— in which 65 it is adapted to fit and slidably move one of a series of elongated, preferably curved, cam surfaces —17— eccentrically arranged with respect to the cylindrical casing —8— and formed preferably integrally with and depending from the cap —9— so that upon rotation of the cap in one direction the bars —14— and their respective wheels —13— are moved inwardly and upon reverse rotation are moved outwardly to vary the operative article-receiving opening between the 70 wheels. When the proper adjustment of the wheels is obtained by rotation of the cap —9— relatively to base —7—, the parts may be held in their desired position by any suitable means, as by tightening the screws —10— or by the use of an additional means, such as thumb screw —18—.

The grooves or depressions in the bars —14— have their bordering walls formed 85 on arcuate lines so as to substantially fit the cam surfaces —17—.

A spring —19— is provided having one end —20— engaged with the base —7— and its opposite end —21— engaged with the 90 cap —9— for normally holding the bars —14— at their limit of outward movement. This normal positioning of the parts may be reversed or re-arranged in any way, the spring constituting a means for preventing 95 rattling or removal of the parts.

The cap —9— is provided with a central opening —22— registering with the opening between the wheels —13— and the opening between the sectional dies —2—. For the purpose of automatically and positively supplying oil, particularly to the die portions of the device, the cylindrical casing —8— carries a cylindrical oil chamber 100 —23— closed at its top by a flexible plate —24— of any suitable material, such as sheet tin, and having a passageway —25— in its bottom communicating with a pipe —26— carried by sleeve —27— having a threaded engagement with the recessed 105 lower portion —28— of the casing forming the chamber —23—. The pipe —26— leads

downwardly and terminates adjacent the sectional dies —2— to discharge oil thereon.

The pipe —29— leads to and is connected with one of the handles —30— of the stock, 5 which handle is hollow and forms a receptacle for oil. Preferably, the pipe —29— is connected to the interior of handle —30— by a valve casing —31— having a movable ball valve —32— therein for normally preventing back flow of the oil from chamber —23— and for preventing the flow of the oil from the hollow handle —30— when the device is not in use.

The communication between chamber 15 —23— and discharge pipe —26— is normally cut off by a valve —33— having its stem projecting upwardly through chamber —23— and provided at its upper end with a ball or enlargement —34— held in substantial contact with the under surface of plate —24— by a spring —35— when the valve —33— is closed.

For the purpose of automatically operating the valve —33— and for drawing oil 25 into the chamber —23— through pipe —29—, one of the wheels —13— is provided with an upwardly projecting cam or ball surface —36— adapted in the rotation of said wheel to contact with one end —37— of a 30 lever —38— pivoted at —39— upon the base —7— and having its opposite end —40— in substantial contact with the upper surface of the flexible plate —24—, preferably directly above the ball —34—. As 35 the end —37— of lever —38— is raised by contact of cam —36— during the rotary movement of the wheel —13—, the end —40— is depressed, depressing the central portion of plate —24—, opening the valve 40 —33— against the action of spring —35— and allowing the discharge of oil through the pipe —26—.

When the plate —24— by its own action 45 returns to normal substantially planar condition, the vacuum produced in chamber —23— draws any oil that may be in pipe —29— into the chamber and the depression of plate —24— not only opens valve —33— but positively forces the oil 50 from the chamber.

Preferably, the wheel —13— having the cam surface —36— is roughened or formed with teeth upon its edge to constitute a friction surface necessitating a positive rotation 55 of the same in contact with the article to be threaded.

Although I have shown and described one particular and specific construction and arrangement of parts as perhaps a preferable embodiment of my invention, I do not desire to limit myself to the same or to any specific construction, as many changes may be made, both in the construction, arrangement and method of operation of the parts, without departing from this invention as 60 set forth in the appended claims.

What I claim is:

1. In a die stock, die members, a movable guiding member, an oil chamber, and means operated by the movement of said guiding member for discharging oil from said chamber to lubricate the die members.

2. In a die stock, die members, a rotatable guiding member, an oil chamber, and means operated by the rotation of said guiding member for discharging oil from said chamber.

3. In a die stock, die members, a rotatable guiding member, an oil chamber having an outlet, a valve controlling said outlet, and means operated by the rotation of said guide member for operating said valve.

4. In a die stock, die members, a rotatable guiding member having a cam surface, an oil chamber having an outlet and a flexible top, a valve closing said outlet and having its stem in substantial contact with said flexible top, a pivoted lever having one end in contact with said flexible top and its opposite end in the path of said cam surface.

5. In a die stock, die members, a rotatable guiding member, an oil chamber having an outlet for discharging oil to lubricate the die members, a valve for said outlet, and means actuated by the rotation of said guiding member for actuating said valve.

6. In a die stock, die members, a rotatable guiding member having a cam surface, an oil chamber having an outlet for discharging oil to lubricate the die members, a valve for said outlet, and a lever having one end adapted for contact with said cam surface upon rotation of said guiding member whereby the valve is actuated to discharge oil.

In witness whereof I have hereunto set my hand this 30th day of March, 1916.

HARRY B. MILLER.
